United States Patent [19]

McGuire

[11] Patent Number: Des. 310,530

[45] Date of Patent: ** Sep. 11, 1990

[54] NON-ELECTRONIC SOUND AMPLIFIER

[76] Inventor: Rex McGuire, 2108 Rodeo Dr.,
Mountain Home, Ark. 72653

[**] Term: 14 Years

[21] Appl. No.: 247,070

[22] Filed: Sep. 21, 1988

[52] U.S. Cl. D14/205

[57] CLAIM

The ornamental design for a non-electronic sound amplifier, as shown and described.

DESCRIPTION

FIG. 1 is a perspective view of a non-electronic sound amplifier showing my new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a right side elevational view thereof; and

FIG. 7 is a left side elevational view thereof.

FIG. 1

FIG. 2

FIG. 3

FIG. 4

Fig. 5

Fig. 6
